ABSTRACT

A foldable tray having a single sheet of material having lines of reduced resistance to bending separating a central base area and first through fourth side areas encircling the base area, the lines of reduced resistance to bending separating the first and second side areas being curved away from each other adjacent a first corner of the base area to cause the base area adjacent the first corner to curve upward when the first and second side areas are bent upward along their respective lines of reduced resistance to bending, each side area having cooperatively disposed fasteners adjacent the adjacent side areas for retaining the side areas when folded upward about the lines of reduced resistance to bending a tab with an opening may be provided integral with one of the side areas for hanging the tray for storage or display. Various embodiments are disclosed.

FOLDABLE TRAY

CROSS-REFERENCE TO RELATED APPLICATION

This application claims the benefit of U.S. Provisional Patent Application No. 60/491,619 filed Jul. 31, 2003.

BACKGROUND OF THE INVENTION

1. Field of the Invention

The present invention relates to the field of receptacles, and more specifically to trays.

2. Prior Art

A tray may be defined as a shallow flat receptacle with a raised edge or rim, used for carrying, holding, or displaying articles. The upturned edges give individual trays a significant height, which can be a disadvantage when it comes to storage of an empty tray. Also, even if identical trays nest, so that they may be stacked at the point of sale, they normally require shelf space, as there is no convenient way to hang them on a display. Also, conventional trays are rectangular, with all four corners being the same. However, in many applications, trays are used to temporarily hold small articles, or liquids, for easy access. When the remainder of the articles or liquid is to be returned to the original container, there is a risk of spillage if the remainder is poured directly from the tray to the original container. The present invention provides a novel tray having novel features that address such matters.

BRIEF DESCRIPTION OF THE DRAWINGS

FIG. 1 is an illustration of one embodiment of an unfolded tray in accordance with the present invention.

FIG. 2 is a top view of a folded tray in accordance with the present invention.

FIG. 3 is a front perspective view of a folded tray in accordance with the present invention.

FIG. 4 is a left side perspective view of a folded tray in accordance with the present invention.

FIG. 5 is a back perspective view of a folded tray in accordance with the present invention.

FIG. 6 is a right side perspective view of a folded tray in accordance with the present invention.

FIG. 7 is a bottom view of a folded tray in accordance with the present invention.

FIG. 8 is an illustration showing the corner detail of an alternate embodiment of an unfolded tray in accordance with the present invention.

FIG. 9 is a bottom view of a folded tray showing the corner detail of FIG. 8 after folding.

FIG. 10 is an illustration showing the corner detail of a still further alternate embodiment of an unfolded tray in accordance with the present invention.

FIG. 11 is a bottom view of a folded tray showing the corner detail of FIG. 10 after folding.

DETAILED DESCRIPTION OF THE PREFERRED EMBODIMENTS

The present invention comprises a foldable tray ideal for holding and pouring of small objects and powders, whether returning the same to their original container or to another container. By way of example, the preferred embodiment disclosed herein is intended for the hobby market to hold embossing powders, beads, glitter, confetti, metallic pow-

ders and the like. The foldable tray is also highly useful for other purposes such as for holding pills for counting or for holding other small items for sorting, counting, easy selection, etc.

5 One embodiment of the foldable tray of the present invention is illustrated in the unfolded condition in FIG. 1. The tray is formed from a sheet of foldable, though semi-rigid, plastic such as, by way of example, polyethylene or polypropylene. These and other plastics, when in relatively 10 thin sheet form, may be folded through a ninety degree-angle many many times before the material at the fold begins to separate.

The sheet of plastic, generally indicated by the numeral 15 20, is preferably die cut in the form shown to define an approximately rectangular form having end flaps 22 and tabs 24 and 26, though otherwise having an approximately rectangular outline. Also formed in the sheet 20 are fold lines 28 defined by lines of reduced resistance to bending. In the preferred embodiment, these lines are lines or regions of 20 reduced material thickness. The fold lines 28 generally define a rectangular plane form, though at one corner curve in region 32 to intersect corner 34 of the plastic sheet 20. Fastened to the plastic sheet are complementary components 25 of plastic snaps 36 and 38, and 40 and 42. In the exemplary embodiment, snap elements 36 are female or male snap elements facing downward and snap elements 38 are male or female snap elements facing upward. With respect to snap elements 40 and 42, either one may be a male snap element, with the other being a female snap elements the two snap 30 elements facing in opposite directions.

To fold the tray, flaps 44 and 46 are folded upward along fold lines 28 to approximately ninety degrees, with tabs 24 and 26 being folded through another ninety degrees along fold lines 48 and 50 so that snap elements 40 and 42 may be 35 snapped together (see FIGS. 2 through 7, illustrating a fully folded tray). Then the remaining two flaps 52 are folded upward and the tabs 22 folded around the outside of the adjacent flap and the snaps snapped together.

The resulting tray is illustrated in FIGS. 2 through 7. The 40 curve of fold lines 28 in regions 32 provides an upward curving pouring spout 54 which prevents material in the tray from accidentally rolling or pouring out through the spout, but still allows easy pouring of the contents in the tray into another container, such as its original container.

45 It should be noted that any or all of tabs 22 may be on the end of the adjacent flap rather than on the flap shown in the illustration of FIG. 1. Also while the folded and assembled tray as shown in FIGS. 2 through 7 is shown with square tabs, this is for illustration convenience only, as preferably 50 the tabs 22 are rounded as shown in FIG. 1 to avoid sharp corners. It is for this reason that the tabs are preferably folded around the outside of the adjacent flap, as doing so helps bury the relatively sharp corner on the adjacent flap in the folded assembly. Alternatively or in addition, the corner 55 on each flap may itself be rounded. These and other variations will be obvious to those skilled in the art.

The foregoing embodiment is well suited for containing and dispensing small, solid objects, but is not suitable for liquids because of the corner configuration used. However, 60 FIG. 8 is an illustration showing the corner detail of an alternate embodiment of an unfolded tray, and FIG. 9 is a bottom view of a folded tray showing the corner detail of FIG. 8 after folding. This corner detail is leak proof, and accordingly, such a tray may be used with solid objects or 65 liquids. The corner has a plurality of lines of reduced resistance to bending 56 separating the adjacent side areas which on folding, forms a pleated, leak proof corner con-

struction. Tabs **58** integral with the side areas may be folded over to be outside the tray, and may be provided with cooperatively disposed complimentary snap fasteners for holding the sides and corners in the folded condition (FIG. 9). Preferably lines of reduced resistance to bending integrally join the tabs to the sides, and if desired, lines of reduced resistance to bending may be provided along the tabs as shown.

A still further alternate embodiment of leak proof corner construction may be seen in FIG. 10 in the unfolded state, and in the folded state in FIG. 11. The corner construction has a corner panel or area **64** integrally coupled to the base area by a line of reduced resistance to bending **60** that is angled with respect to, and joins, the lines of reduced resistance to bending **62** joining the adjacent side areas to the base area. Two additional lines of reduced resistance to bending **66** are provided at each side of the corner area **64**, which on folding of the tray, form a single pleat at each side of each corner area. Of course, one corner of either of these additional embodiments would preferably have the pouring spout hereinbefore described with respect to the first embodiment.

In the embodiments shown, a single pouring spout is shown. However more than one pouring spout might be provided, either identical to the first, such as, by way of example, at an opposite corner of the tray, or perhaps the same or similar in concept, but of different dimensions. For instance, one spout might be relatively wide and the other relatively narrow. This may be useful, by way of example, for pouring powders and materials of small particle size back into small mouth containers using the narrow spout, and using the same tray for larger items such as large beads and pouring the beads back into a larger mouth container using the wider spout. Also, if desired, the tabs **24** and **26** might be made wider, extending to or nearly to the corner **34** on one or more spouts. When the side areas are folded upward and the wider tabs folded over and joined, the spout will be covered, forming a sort of funnel to help facilitate spill proof pouring. Finally, while trays having four side areas are discussed, trays of a lesser or a greater number of side areas, each of the same or different sizes, may incorporate the principles of the present invention. By way of example, area **64** has been referred to herein as a corner panel, though the same could equally be considered another side panel, and could be produced in any relative size. Similarly, foldable trays having three sides are also provide practical implementations of the present invention.

One of the advantages of the present invention is that since the original tray is flat, the same will ship and store very efficiently, taking up little room at a retailer's display area or storeroom. In that regard, tab **56** (FIG. 1) is provided for hanging the tray on a common display rack found in most retail stores. This is to be compared with one piece molded trays which do not stack well or display easily, thereby increasing shipping costs and both display space and storage space. Typically such molded trays also do not include a turned up pouring spout like the present invention, and accordingly, the return of unused material in the tray to its original container, etc., is not as neatly and easily accomplishable as with the present invention. Thus, the present invention provides a very efficient, very useful and very practical tray for a myriad of uses.

What is claimed is:

1. A foldable tray comprising:

a single sheet of material having lines of reduced resistance to bending separating a central base area and a plurality side areas distributed around the base area, the

lines of reduced resistance to bending separating at least two adjacent side areas from the base area being curved away from each other adjacent a respective corner of the base area to cause the base area adjacent the respective corner to curve upward when the adjacent side areas are bent upward along their respective lines of reduced resistance to bending, each side area having cooperatively disposed fasteners adjacent the adjacent side areas for retaining the side areas when folded upward about the lines of reduced resistance to bending.

2. The foldable tray of claim 1 wherein the fasteners are cooperatively disposed male and female snap fasteners.

3. The foldable tray of claim 1 wherein except for the lines of reduced resistance to bending separating at least two adjacent side areas from the base area being curved away from each other, the lines of reduced resistance to bending are substantially straight, and wherein the corners of the sheet of material defined by the intersection of substantially straight lines of reduced resistance to bending having a slit collinear with one of the lines of reduced resistance to bending and extending from a side of the sheet of material to another line of reduced resistance to bending, thereby defining a tab integral with a side area wherein, when the side areas are folded upward about the lines of reduced resistance to bending, each tab may be bent around and fastened to the adjacent side area by cooperatively disposed fasteners.

4. The foldable tray of claim 3 wherein the cooperatively disposed fasteners for fastening the tabs to the adjacent side areas are snap fasteners.

5. The foldable tray of claim 4 wherein side areas having lines of reduced resistance to bending separating the respective side areas from the base area that curve away from each other adjacent a respective corner have outward protruding corner tabs with cooperatively disposed fasteners thereon, so that when the side areas are folded upward about the lines of reduced resistance to bending, cooperatively disposed corner tabs may be bent over the respective corner and the fasteners joined.

6. The foldable tray of claim 1 wherein side areas having lines of reduced resistance to bending separating the respective side areas from the base area that curve away from each other adjacent a respective corner have outward protruding first tabs with cooperatively disposed fasteners thereon, so that when the side areas are folded upward about the lines of reduced resistance to bending, cooperatively disposed corner tabs may be bent over the respective corner and the fasteners joined.

7. The foldable tray of claim 1 wherein the lines of reduced resistance to bending are lines of reduced thickness.

8. The foldable tray of claim 1 wherein side areas having lines of reduced resistance to bending separating the respective side areas from the base area that are straight adjacent a respective corner include a plurality of lines of reduced resistance to bending extending outward to adjacent edges of the sheet, and having corner tabs integral with the adjacent side areas, the lines of reduced resistance to bending extending outward to adjacent edges allowing pleating of the respective corners when the side areas are folded upward about the lines of reduced resistance to bending separating the side areas from the base areas, the corner tabs being bendable over a respective side area and fastenable to an adjacent corner tab to hold the respective corner in the pleated condition.

9. The foldable tray of claim 8 wherein the corner tabs are fastenable by snap fasteners.

10. The foldable tray of claim 1 wherein side areas having lines of reduced resistance to bending separating the respective side areas from the base area that are straight adjacent a respective corner each include corner areas between adjacent side areas, each corner area being coupled to the base area by a line of reduced resistance to bending angled with respect to and joining the lines of reduced resistance to bending coupling the respective side areas to the base area, the corner areas being integrally coupled to each adjacent side area by two lines of reduced resistance to bending emanating from the junction of the lines of reduced resistance to bending separating the corner and respective side area from the base area and extending outward to adjacent edges of the sheet to allow forming a pleat at each side of the respective corner area when the side areas and corner areas are folded upward about the lines of reduced resistance to bending, the side areas adjacent the corner areas having tabs that are bendable over a side area and fastenable to an adjacent corner tab to hold the respective corner area in the upward folded condition.

- 11.** The foldable tray of claim 10 wherein the corner tabs are fastenable by snap fasteners.
- 12.** The foldable tray of claim 1 wherein the sheet is a plastic sheet.
- 13.** The foldable tray of claim 12 wherein the plastic is polyethylene.
- 14.** The foldable tray of claim 12 wherein the plastic is polypropylene.
- 15.** The foldable tray of claim 1 further comprised of a tab 10 with an opening therein, the tab being integral with one of the side areas and configured for use to hang the foldable tray for storage and display.
- 16.** The foldable tray of claim 1 wherein the number of side areas is four.
- 17.** The foldable tray of claim 1 wherein the number of adjacent side areas coupled to the base area by lines of reduced resistance to bending that are curved away from each other adjacent a respective corner is two.
